UNITED STATES PATENT OFFICE.

JOHN S. GREENE, OF ROCHESTER, NEW YORK, ASSIGNOR TO PHOTOSTAT CORPORATION, OF PROVIDENCE, RHODE ISLAND, A CORPORATION OF RHODE ISLAND.

PHOTOGRAPHIC DEVELOPING APPARATUS.

1,381,871.

Specification of Letters Patent. Patented June 14, 1921.

Application filed June 17, 1919. Serial No. 304,789.

To all whom it may concern:

Be it known that I, JOHN S. GREENE, of Rochester, in the county of Monroe and State of New York, have invented certain new and useful Improvements in Photographic Developing Apparatus; and I do hereby declare the following to be a full, clear, and exact description of the same, reference being had to the accompanying drawings, forming a part of this specification, and to the reference numerals marked thereon.

My present invention relates to photography and more particularly to photographic developing apparatus and it has for its object to provide a simple and efficient means for handling and conveying photographic prints as delivered to the developing apparatus from the camera or exposing apparatus. The invention is particularly applicable to the commercial type of camera in which a positive image is taken directly upon sensitive paper, successive lengths of which are reeled through the camera and passed directly through developing and washing mediums after which they are delivered ready for use except for drying. My improvements are directed in part toward a device that will submerge as well as convey the print and which is susceptible of operation in a dark chamber without attention to give uniformly efficient service. To these and other ends the invention resides in certain improvements and combinations of parts, all as will be herein-after more fully described, the novel features being pointed out in the claims at the end of the specification.

In the drawings:

Figure 1 is a side view, partly in section, of a developing apparatus constructed in accordance with and illustrating one embodiment of my invention, an exposing camera associated therewith being also shown in section in a fragmentary way;

Fig. 2 is an enlarged longitudinal sectional view of the print conveyer, the section being taken through the tanks and conveyers in the plane of an inside wall thereof;

Fig. 3 is an enlarged top view of the conveying portion of the apparatus, the rest being broken away;

Fig. 4 is an enlarged section through one of the conveyer sprockets, in detail, and

Fig. 5 is a side view of the machine show-

ing a fragmentary elevation of the driving mechanism.

Similar reference numerals throughout the several views indicate the same parts.

The exposing camera and the general arrangement of the developing apparatus is of a construction well known in the commercial art and referring to Fig. 1, 1 indicates the exposing chamber of the camera and 2 the focal plane thereof along which a continuous strip of sensitive paper is fed from a roll 3 downwardly between feed rollers 4 and 5 operated by a crank 6, shown in dotted lines, or otherwise. Sometimes the strip is severed into the respective exposure areas immediately upon passing the feed rollers, but in the present showing, it is intended to expose and develop the strip by intermittent feeding in a continuous length.

After passing the feed rollers 4 and 5, the strip passes into a liquid container or tray 7, the front end of which is arranged beneath the camera and which contains the developer at a surface level indicated at 8 in Fig. 2 and in so passing into the container or developing tank, the strip is directed rearwardly in the direction of its natural curl by a curved guide 9 and kept from rising to the surface by a submerging guide 10 formed of a grating of longitudinal bars located below the surface level 8.

Near its rear end the developing tank or container 7 is spanned by a shaft 11 having bearings in its side walls and carrying sprocket wheels 12 that cut the plane of the guide 10 to project below it but clear of the smooth bottom 13 of the tank over which the prints slide. This bottom preferably includes a tracking surface 14 for the prints formed in continuation of the guide 9 and terminating at the rear in an inclined runway 15 ending at a tangentially arranged roller 16 at the brim of the tank. A second transverse shaft 17 with similar sprockets 18 is arranged in an elevated position at this point and extending between and driven by the respective units of these two pairs of sprockets 12 and 18 is an endless conveyer indicated generally at C and composed of flexibly connected links 19 carrying successive non-abrasive frictional contact members 20. As shown in Fig. 4, I prefer to use a bar link terminating in relatively transverse eyes 21 for attachment to

each other and carrying a surrounding cylinder of soft rubber 20, the cylinder being of such diameter as to prevent the link from contacting with the same surface as its contact member. Both sets of sprockets 12 and 18 are positively driven as herein-after explained but the conveyer C is so looped between them that the upper stretch thereof, traveling in the direction of the arrow, is taut while the lower stretch, traveling in the opposite direction or rearwardly, is slack and its weight is rested upon the tank bottom 14 and the runway 15, to both of which it conforms.

15 In preparing the machine, the print strip P as received from the feed rollers 4 and 5 is fed under the submerging guide 10 and threaded beneath the conveyers C the sprockets of which are driven at a rate in 20 harmony with the rate of feed at the feed rollers. The conveyers then frictionally engage the print strip, resting against the same by gravity, and keep it traveling rearwardly without placing any strain thereon 25 and while holding it submerged in the developing solution. To these ends, I prefer to make the links 19 of metal and fairly stout so as to have appreciable weight when submerged.

30 In rear of the developing tank 7 is a hypo-tank 22 which is shown, in the present instance, as shorter than the developing tank 7 but which is otherwise fitted in substantially the same way, including a guide 35 9', tracking surface 14', runway 15' and roller 16'. It is also provided with sprocket shafts 11' and 17', but the former is elevated because of the shorter length of the tank and to bring its sprockets 12' close to 40 the sprockets 18 so that the lower stretch of the conveyers C' will run in substantial continuation of the respective conveyers C. The continuous paper strip is thus fed through the developer up the incline 15, 45 over the roller 16 and into the hypo-tank from which it finally emerges at the roller 16' for washing, drying or such other treatments as may be required.

I prefer to drive positively all of the 50 sprocket shafts and also the rollers 16 and 16' and to time them properly with the initial feeding rollers 4-5, I run a sprocket chain 23 from the roller 4 to a sprocket 24 on the first sprocket shaft 11. Another 55 sprocket 25 on the said shaft and a sprocket chain 26 drives shaft 17 through a sprocket 27 thereon, while the sprocket 28 on shaft 11, through a sprocket chain 29, communicates motion through a sprocket 30 to shaft 60 11'. A second sprocket 32 on shaft 11' drives sprocket chain 31 over a sprocket 33 on shaft 17'. As shown in Fig. 5, gears 34 and 35 on shafts 17 and 17', respectively, drive gears 36 and 37 on the shafts of rollers 16 and 16', respectively. It may in some cases

be desirable to gear sprockets 12' and 18' so that they run a little faster than sprockets 12 and 18 so that there will be no danger of the print crumpling or looping as it passes from conveyers C to conveyers C'. 70

Unless operated in a dark room, both tanks and the conveying mechanism described will be suitably housed in a light-tight casing communicating with the camera casing, but it has not been deemed necessary to show this provision herein as it is commonly employed in the art. 75

I claim as my invention:

1. The combination with a supporting element having a surface over which photographic prints are adapted to slide, and driving gear, of a flexible conveyer operated by the latter to traverse the surface and composed of successive non-abrasive contact members adapted to frictionally engage the print. 80

2. The combination with a supporting element having a surface over which photographic prints are adapted to slide, and driving gear, of a flexible conveyer operated by the latter to traverse the surface and composed of a core of heavy material carrying successive non-abrasive contact members adapted to be pressed by gravity against the print and to frictionally engage it. 90

3. The combination with a supporting element having a surface over which photographic prints are adapted to slide, of a flexible endless conveyer having a slack stretch adapted to traverse said surface in gravity contact therewith, sprockets arranged above said surface and operating to engage and drive said slack stretch of the conveyer, the conveyer being composed of successive non-abrasive contact members adapted to frictionally engage the print and propel it along the surface. 100

4. The combination with a photographic developing fluid receptacle having a smooth bottom terminating in an inclined runway 110 over the surfaces of which bottom and runway photographic prints are adapted to slide and be finally delivered from the receptacle, of a flexible endless conveyer having a slack stretch adapted to traverse said surfaces in gravity contact therewith, sprockets arranged above said surfaces and operating to engage and drive said slack stretch of the conveyer, the conveyer being composed of successive non-abrasive contact members adapted to frictionally engage the print and propel it along the surface. 115

5. The combination with a liquid container having at its bottom a smooth supporting surface over which photographic prints are 125 adapted to slide, and driving gear, of a flexible conveyer operated by the latter to traverse the surface and composed of a core of heavy material adapted to submerge the print, said core carrying successive non- 130

abrasive contact members adapted to be pressed by gravity against the print and to frictionally engage and propel it.

6. The combination with a supporting element having a surface over which photographic prints are adapted to slide, and driving gear, of a flexible conveyer operated by the latter to traverse the surface and composed of successive non-abrasive contact members adapted to frictionally engage the print, said contact members being individually carried by the links of a metal chain.

7. The combination with a liquid con-

tainer having at its bottom a smooth supporting surface over which photographic prints are adapted to slide, and driving gear, of a flexible conveyer operated by the latter to traverse the surface and composed of a chain having bar links terminating in loops or eyes by which they are connected together and successive non-abrasive contact members surrounding the bars and of greater diameter than the chain, said members being adapted to be pressed by gravity against the print and to frictionally engage and propel it.

JOHN S. GREENE.
